UNITED STATES PATENT OFFICE.

WINFIELD S. PATTIN, WILLIAM M. MORSE, AND DOUGLAS P. PATTIN, OF MARIETTA, OHIO.

STEAM-ENGINE VALVE.

SPECIFICATION forming part of Letters Patent No. 469,173, dated February 16, 1892.

Application filed November 7, 1891. Serial No. 411,237. (No model.)

To all whom it may concern:

Be it known that we, WINFIELD S. PATTIN, WILLIAM M. MORSE, and DOUGLAS P. PATTIN, citizens of the United States, residing at Marietta, in the county of Washington and State of Ohio, have invented certain new and useful Improvements in Steam-Engine Valves, of which the following is a specification.

Our invention relates to improvements in that class of steam-valves that are employed on steam-pumps and like engines of reciprocating movement where the main steam-valve is moved by a secondary steam-piston, which in turn is moved by an auxiliary valve, said auxiliary valve being operated by knockers moved by the direct action of the main steam-piston.

Our invention more particularly relates to improvements in the arrangement of steam-ports, valve-seats, steam-pockets, &c., which we secure by a central plate, and to the peculiar form and arrangement of the auxiliary valve and tappets or knockers, as hereinafter fully described.

Figure 1 is a vertical longitudinal section of a steam-cylinder, valve, and valve-chest, taken on lines E² F², Fig. 4. Fig. 2 is a vertical longitudinal section of a steam-cylinder, main and auxiliary valves, and steam-chest on line G² H², Fig. 5. Fig. 3 is a vertical longitudinal section of a steam-cylinder, auxiliary valve, steam-chest, and knockers on line I² J², Fig. 5. Fig. 4 is a vertical cross-section of a steam-cylinder, valves, and chest on line A² B², Fig. 1. Fig. 5 is a vertical cross-section of a steam-cylinder, valves, and chest on line C² D², Figs. 2 and 3. Figs. 6 and 7 are a bottom and top plan, respectively, of the central plate N. Figs. 8 and 9 are a bottom and top view, respectively, of the auxiliary valve X. Figs. 10 and 11 are side views of the two knockers or tappets K K'. Fig. 12 is a top plan of main-cylinder casting, showing knocker-grooves, main steam-ports S S', and exhaust-port Y.

Similar letters refer to similar parts throughout the several views.

P is the main steam-piston, and Z the piston-rod.

V is the main steam-valve, and A the valve

or secondary piston, having heads of unequal area and provided with suitable packing-rings.

N is the central plate, (shown in top and bottom views in Figs. 7 and 6, respectively,) in which plate are the main steam-ports S S', the main exhaust-port E, the exhaust-port Y for auxiliary valve, the auxiliary-valve steam-ports C C', leading to ends of piston A, the steam-pockets Q Q' to admit steam under auxiliary valve, and the cavities U U', through which the knockers K K' project into the cavities T T' in under side of auxiliary valve. (See Fig. 8.) The central plate N rises into the steam-chest (see Fig. 1) and forms the seats of main valve V and also of auxiliary valve X. It further forms a steam-tight joint between the two knocker-cavities O O', Fig. 12, and in connection with the auxiliary valve X forms a steam-tight joint between the two knockercavities O O', so that no steam can blow through from one end of cylinder to the other.

X is the auxiliary valve, (shown in top and bottom views in Figs. 9 and 8, respectively,) in which T T' are cavities, into which the knockers K K' project in order to move the valve.

F F' are square openings through the valve, through which live steam is admitted from the steam-space L, Figs. 4 and 2, to the ends of auxiliary piston through the steam-pockets Q Q' in central plate and the steam-pockets R R' in under side of auxiliary valve, thence (see Fig. 2) through the ports C C', Fig. 6, to end of piston A, Fig. 1. The pockets R R' in under side of auxiliary valve are both live-steam and exhaust pockets, since when one is a live-steam the other is an exhaust pocket; but the steam-pockets Q Q' in center plate are always live-steam pockets.

The knockers K K', Figs. 10 and 11, slide in grooves O O' in main-cylinder casting, projecting downward into the main cylinder (see Fig. 3) so as to be moved by the main steam-piston P, the heads of main cylinder having suitable recesses into which knockers move, so that by no possibility can they be caught and broken by main piston P. The knockers K K' also project upward into cavities in un-

der side of auxiliary valve, as heretofore described.

The exhaust-opening Y under auxiliary valve is made very large, as shown, in order to insure the seating of said valve when working in a vertical position, as when applied to locomotive air-pumps.

The knockers K K', being entirely within the cylinder-casting and covered by the central plate and auxiliary valve, and being two solid pieces of wrought iron or steel, are not liable to any injury or to getting out of order, as might be the case in hinged tappets or connected tappets.

15 The method of operation is as follows: Referring to Fig. 1, the action of the main valve V over the two induction-ports S S' and the intermediate exhaust-port E is the ordinary and well-known action of the D-valve—that is to say, in the position shown in this view steam is entering at the right-hand end of the cylinder and is being exhausted from the left-hand end. To shift the main valve, the piston-valve A is operated upon by steam through the port C C' as follows: The main piston having traveled to the end of its stroke, as shown in Figs. 1, 2, and 3, the knocker K is moved to the right, as shown in Fig. 3, carrying with it the auxiliary valve X to the position shown in Fig. 25

30 2. Steam is then admitted from the central cavity of steam-chest L (see Fig. 4) through the opening F, Fig. 2, in auxiliary valve, thence through steam-pocket Q in central plate, thence through steam-pocket R in under side 35 of auxiliary valve, through port C in central plate, and in steam-chest to right-hand end of piston A, thus throwing piston A, carrying main valve V, to position shown in Fig. 2. At this time steam is admitted through main 40 port S to right-hand end of main piston P, when conditions are ready to commence return stroke. Meantime exhaust has taken place from left-hand head of valve-piston A, through port C' and valve-pocket R', to main 45 exhaust Y.

We are aware that various forms of auxiliary valves operated by knockers, levers, or

tappets in the cylinder have been heretofore provided. Our invention is chiefly distinctive in the separate central plate N, in which 50 the various ports or openings are formed and through which the knockers operate upon the auxiliary valve. This plate entirely separates the two knocker-chambers and prevents leakage of steam from one to the other by 55 making close contact between the lower side of the auxiliary valves and the top side of the cylinder at a point between the knockers. This enables us to cheaply construct an engine of this type with but few parts and with 60 no necessity of any nicety of adjustment. Furthermore, all the joints are ground joints, and all gaskets are done away with.

Having thus described our invention, what we claim as new, and desire to secure by Letters Patent, is—

1. In a steam-cylinder having a piston-actuated slide-valve, the combination of the sliding knockers K K', the auxiliary valve X, engaged by said knockers and moving with them, and the intermediate plate N, having openings through which its knockers pass in connecting with the valve, the said plate serving to make a tight connection between the lower side of said valve and the upper surface of the cylinder at a point between the knockers, whereby the knocker-chambers are entirely separated from each other, substantially as shown and described.

2. The central plate N, having the main 80 ports E S S', knocker-holes U U', passages C C', and recesses Q Q', in combination with the auxiliary valve X, with knocker-recesses T T', openings F F', and recesses R R', and the knockers K K', sliding in the cylinder and 85 extending through the central plate into the recesses T T' of the auxiliary valve, substantially as shown and described.
